United States Patent Office

Des. 222,369
Patented Oct. 19, 1971

222,369

MODULAR CABINET

Charles E. Schroer, Columbus, Ind., and John J. Hamilton, Avon, Conn., assignors to Hamilton Cosco, Inc., Columbus, Ind.

Original design application Dec. 26, 1968, Ser. No. 15,125, now Patent No. 217,558. Divided and this application Mar. 2, 1970, Ser. No. 21,677

Term of patent 14 years

Int. Cl. D6—04

U.S. Cl. D33—19

Fig. 1

Fig. 2

Fig. 3

Fig. 4

FIG. 1 is a front elevation of a modular cabinet showing our design;

FIG. 2 is a side elevation of the cabinet shown in FIG. 1;

FIG. 3 is a top plan view of the cabinet shown in FIG. 1; and

FIG. 4 is a rear elevation of the cabinet shown in FIG. 5.

This application is a divisional application of our co-pending application Ser. No. 15,125, filed Dec. 26, 1968, and now Pat. No. D. 217,558.

We claim:

The ornamental design for a modular cabinet, as shown.
